SETBACK SWITCH

John W. Busacker and Richard L. Maneval,
Houston, Tex., assignors to the United States of
America, as represented by the Secretary of
the Navy

Application August 3, 1943, Serial No. 497,230

4 Claims. (Cl. 200—52)

1

This invention relates to a switch, and more particularly to an electrical switch which may be mounted within a projectile to close at least a portion of an electrical detonating circuit when the projectile is fired.

An object of the invention is to provide a switch of the character indicated which will remain in opened position during normal handling of the explosive projectile in which the same is mounted, and which will be automatically actuated to close upon the application of setback force created by the acceleration of the projectile when the same is fired from a gun.

Other objects of the invention are to provide a setback switch which may be easily made and assembled and wherein the numerous mechanical operating parts usually employed in prior art devices of this nature have been eliminated.

Still other objects of the invention will be apparent from the following description of the drawings, in which:

Fig. 1 is a longitudinal sectional view of a portion of a projectile and a diagrammatical view of the switch mounted therein, the switch being incorporated within an electrical detonating circuit.

Fig. 2 is an enlarged sectional view of the switch when in its opened position.

Fig. 3 is an enlarged sectional view of the switch when in its closed position.

Referring now to the drawings, and particularly Fig. 1 thereof, the letter P generally indicates a portion of a projectile which has at least a portion of an electrical detonating circuit C therein. The circuit C is provided with a battery B or other suitable source of current.

The body of the device 10 is formed of insulating material, and may be a portion of a body of an amplifier or other component within the projectile. An upstanding sleeve 11 is formed integrally with the body 10 and has a bore 12 extending therethrough. The bore 12 is provided with an enlarged portion 13 at its rear or lower end, the enlarged portion 13 defining a shoulder 13'. A cup-shaped contact member 14, formed of suitable conductive metal, is mounted in the enlarged portion 13 of the bore 12 and bears against the shoulder 13'. The contact member 14 has an annular inwardly flared portion 15 adjacent to the forward or top portion thereof. It will be noted that the diameter of the inwardly flared portion 15 of contact member 14 is slightly less than the diameter of bore 12. The contact member 14 is secured within the enlarged portion 13 of bore 12 by means of a metallic bar 16 which

2

underlies the rear or bottom end of the contact member 14 and wedges the latter against the shoulder 13'. The bar 16 may be formed as an integral part of a post 17. The post 17 is provided with an internally threaded portion 18, and is secured to the body member 10 by means of a screw threaded bolt 19 which extends through a bore in the body 10. Thus, one side of the circuit extends from the battery B to post 17, through bar 16 and then to contact member 14.

The bore 12 has an enlarged portion or recess 20 formed in its forward or upper end thereof, the recess 20 defining a shoulder 21. A disc 22, preferably of metal, is mounted within the recess 20 and rests on shoulder 21, the disc 22 having a centrally positioned aperture therein for receiving a hollow stud 23, a wire 24, which forms the other side of circuit C, extends through the aperture in disc 22 and into the bore 12. The stud 23 and disc 22 rigidly support wire 24 to the upper portion of stem 11, as shown in Figs. 2 and 3. The wire 24 has a plurality of coils or convolutions 25 therein, and its end is soldered or otherwise secured at 26 to the bottom of an elongated substantially U-shaped contact sleeve 27. The contact sleeve 27 is formed of suitable conductive metal and is loosely mounted within bore 12 for longitudinal movement therein. Sealing wax or the like, 28, is placed in recess 20 over disc 22 to seal the latter within the stem 11.

The wire 24 is of suitable gauge so that, when shortened by the convolutions 25, it will support contact sleeve 27 in the upper or forward portion of bore 12 in spaced relation to the stationary contact member 14, as shown in Fig. 2. The parts will remain in this position under normal handling of the projectile in which they are mounted, thereby maintaining the electrical detonating circuit C opened.

The operation of the switch will be readily apparent from the foregoing description. When the parts are in the position shown in Fig. 2, the switch is opened and circuit C is broken. When the projectile is fired, the acceleration thereof creates a setback force which is sufficient to throw the contact sleeve 27 rearwardly against the tension of the convolutions 25 formed in wire 24. As the contact sleeve 27 slides rearwardly in bore 12, it forms a "clinch" type of contact with contact member 14 by contacting the annular inwardly flared portion 15, as shown in Fig. 3. The wire 24 is sufficiently ductile so that when the convolutions 25 are partially pulled out to elongate the wire, the convolutions will stay in their extended positions and will not tend to urge the contact

sleeve forwardly. Thus, when the projectile is fired, contact will be made between sleeve 21 and contact member 14, thus closing the circuit C to arm at least a portion of the electrical detonating circuit. If desired, a pigtail connection may be made to the contact member 14 in place of the bar 16.

We claim:

1. A setback switch adapted to be mounted within a projectile to close at least a portion of an electrical detonating circuit upon the application of setback force created when the projectile is fired comprising a body member of insulating material having a stem extending therefrom, a bore in said body member extending through said stem, said bore having an enlarged portion adjacent to one end thereof, a stationary cylindrical contact member having an annular inwardly flared portion mounted in said enlarged portion of said bore, a contact sleeve positioned in said bore capable of sliding therein upon the application of setback force created when the projectile is fired, and means for maintaining said sleeve in spaced relation with said stationary contact member until setback force is created and for permitting said sleeve to slide into engagement with said annular inwardly flared portion of said stationary contact member after setback force is created, said means including an extendible member secured to said sleeve.

2. A setback switch adapted to be mounted within a projectile to close at least a portion of an electrical detonating circuit upon the application of setback force created when the projectile is fired comprising a body member of insulating material having an integral stem extending therefrom, a bore in said body member extending through said stem, said bore having an enlarged portion adjacent to one end thereof, a stationary cylindrical contact member having an annular inwardly flared portion mounted in said enlarged portion of said bore, a contact sleeve positioned in said bore capable of sliding therein upon the application of setback force created when the projectile is fired, and means including a wire forming a portion of the electrical detonating circuit having one end secured to said sleeve for maintaining said sleeve in spaced relation with said stationary contact member until setback force is created and for permitting said sleeve to slide into engagement with said annular inwardly flared portion of said stationary contact member after setback force is created.

3. A setback switch adapted to be mounted within a projectile to close at least a portion of an electrical detonating circuit upon the application of setback force created when the projectile is fired comprising a body member of insulating material having an integral stem extending therefrom, a bore in said body member extending through said stem, said bore having an

enlarged portion adjacent to each end thereof, a stationary cylindrical contact member having an annular inwardly flared portion mounted in one of said enlarged portions of said bore, a disc having an aperture therein mounted in the other enlarged portion of said bore, a contact sleeve positioned in said bore capable of sliding therein upon the application of setback force created when the projectile is fired, and means for maintaining said sleeve in spaced relation with said stationary contact member until setback force is created and for permitting said sleeve to move into engagement with said stationary contact member after setback force is created, said means including a wire which forms a portion of the electrical detonating circuit having a plurality of convolutions therein, said wire extending through the aperture of said disc into said bore and being secured at its end to said contact sleeve.

4. A setback switch adapted to be mounted within a projectile to close at least a portion of an electrical detonating circuit upon the application of setback force created when the projectile is fired comprising a body member of insulating material having an integral stem extending therefrom, a bore in said body member extending through said stem, said bore having an enlarged portion adjacent to each end thereof, a stationary cylindrical contact member having an annular inwardly flared portion mounted in one of said enlarged portions of said bore, means including a part of the electrical detonating circuit for securing said contact member within said bore, a disc having an aperture therein mounted in the other enlarged portion of said bore, a contact sleeve positioned in said bore capable of sliding therein upon the application of setback force created when the projectile is fired, and means for maintaining said sleeve in spaced relation with said stationary contact member until setback force is created and for permitting said sleeve to move into engagement with said stationary contact member after setback force is created, said means including a wire which forms a portion of the electrical detonating circuit having a plurality of convolutions therein, said wire extending through the aperture in said disc into said bore and being secured at its end to said contact sleeve.
